CLAIM

The ornamental design for a modular bottle as shown and described.

DESCRIPTION

1. Modular bottle
2. Portion of modular bottle
3. Portion of modular bottle
4. Portion of modular bottle
- 1.1 : Perspective
- 1.2 : Front
- 1.3 : Top
- 1.4 : Bottom
- 1.5 : Right
- 1.6 : Cross sectional
- 1.7 : Exploded
- 2.1 : Perspective
- 2.2 : Front
- 2.3 : Top
- 2.4 : Bottom
- 2.5 : Right
- 2.6 : Cross sectional
- 3.1 : Perspective
- 3.2 : Front
- 3.3 : Top
- 3.4 : Bottom
- 3.5 : Cross sectional
- 3.6 : Reference exploded view with seal
- 4.1 : Perspective
- 4.2 : Front
- 4.3 : Top
- 4.4 : Bottom
- 4.5 : Cross sectional

1 Claim, 24 Drawing Sheets
